UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,284,392.

Specification of Letters Patent. Patented Nov. 12, 1918.

Application filed October 20, 1916. Serial No. 123,733.

To all whom it may concern:

Be it known that I, ALBEN E. LUNDELL, a citizen of the United States, residing at New York, in the county of Bronx and State of New York, have invented certain new and useful Improvements in Telephone Systems, of which the following is a full, clear, concise, and exact description.

This invention relates to telephone exchange systems, and more particularly to telephone exchanges in which a selectively operable switching device, such as an automatic connector switch, may be controlled to seize a line leading to a telephone station, or one of a plurality of lines leading to a private branch telephone exchange.

In telephone exchange systems in which a connector switch is arranged to seize either an idle private branch exchange line or an idle direct telephone line, the releasing means provided for the connector switch must be operated if the desired direct line tests busy, but the operation of such releasing means must be delayed while testing private branch exchange lines until an idle private branch exchange line has been found or the condition of the last private branch exchange line has been tested. Only if the last line is busy, will the releasing means be operated.

It has been proposed in the terminal bank of the connector to identify the terminals of all the private branch exchange lines except the last one by current of a certain polarity, and the terminal of the last private branch exchange line and the terminals of direct lines by a certain other polarity. Responsive to these different polarities, a differentially wound or a polarized relay was provided to control in its contacts the operation of the releasing means.

In order to obviate the necessity of identifying the various lines by current of different polarities, it has been proposed to provide an arrangement in which all the lines terminating at a connector switch are identified by current of the same polarity. In such arrangements, however, separate means are provided for controlling the testing of private branch exchange lines and separate means for controlling the testing of direct lines, or, in other words, two test wipers or brushes are provided for each connector switch.

It is the object of the present invention to do away with the necessity of providing dif-

ferentially wound or polarized relays, and with the necessity of identifying private branch exchange and direct lines by current of different polarities. With this object in view, the present invention provides an arrangement in which all the lines terminating at a connector switch are identified by current of the same polarity, a single means being provided at the connector switch for controlling the operation of the releasing means or for governing the hunting operation of said switch.

The drawings, with Figure 1 placed at the left of Fig. 2, and with Figs. 3 and 4 placed below Figs. 1 and 2, respectively, diagrammatically represent a telephone system employing the present invention.

In the drawings a plurality of sequence switches are indicated. These sequence switches may be similar in structure to that shown in the patent to Reynolds and Baldwin No. 1,127,808, and similar in operation and function to the corresponding sequence switches shown in the patent to McBerty No. 1,125,579.

Each of the sequence switches is provided with a master contact. In each instance, the master contact is shown on the drawings immediately above the power magnet of the sequence switch with which it is associated, and is indicated by a reference character, the hundreds digit of which is the same as that of the sequence switch it controls. These master contacts are opened only in the sequence switch positions indicated by the reference characters adjacent thereto and, therefore, indicate the stopping positions of the sequence switches. All the other sequence switch contacts are open in all positions except those indicated by the reference characters adjacent thereto. The contacts governed by each of the several sequence switches are separated from those governed by the others by the confines of the sheets of the drawings. Each sequence switch contact is indicated on the drawings by a reference character, the hundreds digit of which is the same as the hundreds digit of the sequence switch governing it.

The selecting switches, as herein shown, are of the type well known in the art, where in the brush shaft is raised or lowered by contact with one of a pair of constantly driven power drums which rotate in opposite directions. The brush shaft is brought into

engagement with one of these drums through the action of the up-drive clutch magnet or the down-drive clutch magnet, in a manner clearly disclosed in the patent to Craft and

5 Reynolds, No. 1,123,696, January 5, 1915.

The circuits for operating these selecting switches have not been fully disclosed, since they are clearly shown and described in the patent to Lundell, No. 1,168,319, January

10 18, 1916.

The operator's controlling device or keyboard and the registers or recording devices which are shown in Fig. 4 of the drawing and a set of counting relays shown in Fig. 15 3, are similar in construction, arrangement and operation to those disclosed in the above mentioned Patent No. 1,168,319.

It is believed that the present invention will be best understood by establishing a 20 connection from a calling subscriber at A to a called subscriber at B. When the calling subscriber removes his receiver from the switchhook, the line relay 112 is actuated in the well-known manner to close a local energizing circuit to light the lamp signal 113. This signal indicates to a connecting operator that a call has originated on this line. The operator then inserts an answering plug 114 into the calling jack 115. This completes a circuit which may be traced from 25 grounded battery, winding of relay 116, sleeve of plug 114, sleeve of jack 115, the winding of cut-off relay 117 to ground. The cut-off relay is energized and operates to 30 deenergize the line relay 112 and the lamp signal 113. Simultaneously, relay 116 is operated and closed a circuit to move the district sequence switch 100 out of position 1, which circuit extends from grounded 35 battery, magnet of sequence switch 100, contact 102 (1), front contact and armature of relay 116, to ground. In position 2 of the sequence switch 100, a circuit is completed to move the cord finder sequence switch out of 40 position 1 and into position 2 which is established from grounded battery, magnet of sequence switch 300, contact 302, conductor 134, contact 103 (2) to ground. As soon as sequence switch 300 leaves position 1, it 45 completes circuits (not shown) to associate an idle sending device with the cord circuit to which the calling line has been connected.

Upon the extension of the calling line to the cord, the operator depresses listening-in 55 key 121 and thus telephonically connects her head set with the substation apparatus of the calling subscriber.

When the operator has ascertained the 60 number of the desired line, she depresses one of the hundred series of keys indicated at 409, one of the tens series of keys at 410 and one of the units series of keys at 411 in accordance with the designation of the desired line. In response to the depression of 65 one of these keys in each of the series, as

soon as the sequence switch 300 reaches position 2, the hundreds register 400, the tens register 500 and the units register 600 assume set positions in accordance with the operated keys of the key set.

The operating circuit of the register 400 extends from grounded battery, contact 306 (2), magnet of register 400, back contact and armature of stop relay 402 and conductor 403 to ground. The register continues 75 to rotate until its operating circuit is interrupted at the back contact and armature of stop relay 402. This takes place when the stop relay 402 is energized. It will be understood that the depression of one of the numeral keys 409 operates to connect ground to one of the contacts 408 of register 80 400. Assuming that numeral key 412 is depressed, then a ground connection will be established through depressed numeral key 412 to contact 408 (1). As soon as register 400 is rotated, in this case to position 1, the energizing circuit for the stop relay 402 is completed from grounded battery, relay 402, contact 408 (1) and depressed key 412 90 to ground.

The operating circuit for the register 500 may be similarly traced from grounded battery, contact 306, conductor 404, magnet of the register 500, back contact and armature 95 of the stop relay 406, conductor 403, to ground. In response to the completion of this circuit the register 500 rotates until it assumes a position corresponding to the depressed tens key at which time the stop relay 406 is energized to open the circuit just described. The energizing circuit for the relay 406 extends from grounded battery, conductor 417, winding of the stop relay 406, contact 414, key 415, to ground. The 100 units register 600 is likewise operated over a circuit traceable from grounded battery, contact 306, conductor 405, magnet of the register 600, back contact and armature of stop relay 407, to ground. The units register 105 600 also rotates until the stop relay 407 is energized over a circuit completed from grounded battery, winding of the stop relay 407, contact 418, key 419, to ground.

As soon as the sequence switch 300 reaches 115 position 2, which takes place during the operation of the setting of the registers just described, the line relay 118 is energized over the fundamental circuit which extends from grounded battery, winding of relay 118, contact 104 (2), conductor 119, stepping relay 308, back contact and outer armature of the upper zero counting relay 309, contact 304 (2), conductor 120, contact 107 (2 to 3), to ground. As soon as relay 118 120 is energized it completes a circuit to move the sequence switch 100 out of position 2. This circuit extends from grounded battery, magnet of sequence switch 100, conductor 129, contact 106 (2), front contact 130

1 right hand armature of relay 118, to ground. As soon as sequence switch 100 reaches position 3, a locking circuit is completed for relay 118 from grounded battery, winding, front contact and left hand armature of relay 118, contact 104 (2 to 3); over the circuit previously traced for relay 118. In position 3 of the district sequence switch 100, a circuit is completed for the updrive 10 magnet 123 which extends from grounded battery, magnet 123, contact 105 (3), front contact and right hand armature of relay 118, to ground. The selector switch 131 starts to move its brushes 132, 133 and 135 15 over the groups of trunk terminals of the switch and to move commutator brush 126 over the conducting segments of commutator 125. As the commutator brush 127 encounters the conducting segments of commutator 125, a circuit in shunt of the fundamental circuit previously described is completed from ground, through brush 126, a conducting segment of the commutator 125, conductor 128, contact 104 (3), left hand 20 armature, front contact and winding of relay 118, to grounded battery.

It will be understood that the setting of the register 400 serves to complete a circuit to determine which relay of the chain 25 of counting relays shall be actuated. In the present case this circuit extends from grounded battery, conductor 310, counting relay 311, back contact and armature of relay 312, conductor 314, register contact 413 (1), conductor 414, contact 307 (2), front contact and armature of stepping relay 308, to ground. The lower counting relay 311 attracts its armature, and closes a locking 30 circuit including the windings of relays 311 and 312. Relay 312, however, is short-circuited until the stepping relay 308 is short-circuited by the shunt circuit previously described as extending through the commutator 125. The upper counting relay 312 then 35 attracts its armature, whereupon a circuit is completed from grounded battery, conductor 310, lower zero counting relay 315, front contact and armature of relay 312, conductor 314, over the remainder of the circuit 40 previously described. Relay 315 attracts its armature, and prepares a circuit for relay 309, but this relay is short-circuited until the stepping relay 308 again deenergizes. The upper zero counting relay 309 is then 45 energized over a circuit which may be traced from grounded battery, conductor 310, relay 315, relay 309, front contact and armature of relay 315, contact 305, to ground. Relay 309 attracts its armature and at its 50 outer armature interrupts the fundamental circuit previously described. At its inner armature and front contact it completes a circuit to move the sequence switch 300 out of position 2. This circuit extends from 55 grounded battery, magnet of sequence switch

300, front contact and inner armature of relay 309, contact 305 (2), to ground. Sequence switch 300 continues to move until it reaches position 4, by reason of a circuit completed through its master contact 301. 70 When the sequence switch 300 moved out of position 2, the chain of counting relays locked up during the sending of impulses corresponding to the hundreds digit of the desired number, are deenergized. 75

When the upper zero counting relay 309 interrupts the fundamental circuit it causes relay 118 to deenergize and open the circuit of magnet 123, whereupon the selector is arrested with its wipers in operative relation to a group of trunk terminals corresponding to the hundreds key depressed, which is key 412 in the case assumed. 80

Relay 118 closes a circuit from ground, through its armature and back contact, sequence switch contact 106 (3), conductor 129 and the power magnet of sequence switch 100 to grounded battery for moving this sequence switch into position 11. While the sequence switch is moving from position 3 to position 11 the selector hunts for an idle trunk in the selected group in a manner described in Patent No. 1,168,319 and when an idle trunk is seized, the relay 229, which controls the release of the connector, is energized over a circuit extending from grounded battery, winding of relay 229, conductor 137, test terminal, and test brush 135 to ground. 85

In position 11 of sequence switch 100 the fundamental circuit, previously described, is extended through the brushes 132 and 133 of the first selector and the trunk line with which they are now in engagement, to the connector. As soon as this takes place the line relay 212 is energized over a circuit extending from grounded battery, contact 209 (1), over the upper side of the line, brush of the first selector, contact 109, conductor 119, stepping relay 308, outermost armature, 100 and back contact of the upper zero counting relay 309, contact 304 (4), conductor 120, contact 108 (11), a brush of the first selector, lower side of the line, contact 210 (1 to 4), to ground. The relay 212 is energized 105 and at its left-hand armature completes a locking circuit which may be traced from grounded battery, left-hand armature and front contact of relay 212, contact 209 (1 to 4), over the fundamental circuit just described. At the right-hand armature of relay 212, a circuit is completed to move the sequence switch 200 out of position 1. This circuit may be traced from grounded battery, magnet of the sequence switch 200, contact 202 (1), right-hand armature and front contact of relay 212, to ground. In position 120 2 of the sequence switch, an operating circuit for the high-speed up-drive magnet 213 is completed from grounded battery, mag- 125

net 213, contact 203 (2), right-hand armature and front contact of relay 212, to ground. As the commutator brush 216 in the upward movement of connector encounters a conducting segment 214, a circuit in shunt of the fundamental circuit for controlling the counting relays is completed from grounded battery, relay 212, left-hand armature and front contact of this relay, 10 contact 208 (2), conducting segments 214 of commutator 215, commutator brush 216, contact 205 (10 to 8), to ground. The counting relays are again operated during the tens series of impulses in the manner 15 previously described, and when the upper zero counting relay 309 is again energized a circuit is completed from grounded battery, magnet of sequence switch 300, front contact and armature of relay 309, contact 20 305 (4) to ground, to move this sequence switch out of position 4. Sequence switch 300 continues to rotate until it reaches position 6, by reason of a circuit completed through its master contact 301. At the close 25 of the tens series of impulses the brushes 236, 237 and 238 of the connector are in operative relation to the terminals of the desired group. The fundamental circuit is now interrupted at the outer armature and 30 back contact of the upper zero counting relay 309. The relay 212 thereupon deenergizes, and completes a circuit to move the sequence switch 200 out of position 2. This circuit may be traced from grounded battery, magnet of sequence switch 200, contact 202 (2), right-hand armature and back contact of relay 212, to ground. The register 600 now operates in a manner similar to the operation of register 400 to determine the 35 first relay of a chain of counting relays which are actuated as the units impulses are transmitted. The fundamental circuit is re-established as soon as the relay 309 deenergizes and causes the relay 212 to be energized and to attract its armatures. This completes a circuit to move the sequence switch 200 out of position 3, which may be traced from grounded battery, magnet of sequence switch 200, contact 202 (3), right- 40 hand armature and front contact of relay 212, to ground. The energization of relay 212 also completes an operating circuit for the slow speed up-drive magnet 218. This circuit extends from grounded battery, magnet 45 218, contact 203 (4), right-hand armature and front contact of relay 212, to ground. This operation of the up-drive magnet places the brushes 236, 237 and 238 of the connector in engagement with the desired line, or in engagement with the first 50 of a group of P. B. X. lines as the case may be. At the close of the directive movements of the connector switch, the fundamental circuit is again interrupted at the outer armature and contact of relay 309 and the relay 55

212 is caused to retract its armatures. This completes a circuit to move the sequence switch 200 out of position 4 which is completed from grounded battery, magnet of sequence switch 200, contact 202 (4), right-hand armature and back contact of relay 212, to ground. Sequence switch 200 continues to move until it reaches position 7, by reason of a circuit completed at its master contact 201. Simultaneously with the energization of relay 309, the sequence switch 300 is moved from position 6 to its normal position by an operating circuit previously described.

When the sequence switch 300 reaches position 8 after the sending device has completed its operation, a circuit is completed to move the sequence switch 100 out of position 11. This circuit may be traced from grounded battery, magnet of sequence switch 100, contact 102 (11), conductor 136, contact 303 (8 to 15), to ground. The sequence switch 100 continues to move until it reaches position 16, by reason of an operating circuit completed at its master contact 101.

In position 7 of the sequence switch 200, test relay 219 is energized over a circuit which may be traced from grounded battery, left-hand winding of this relay, contact 206 (7), to ground. If the selected line is busy the relay 219 remains locked up in a manner that will hereinafter be described. At the left-hand armature of relay 219, a circuit is completed for moving the sequence switch 200 out of position 7. This circuit extends from grounded battery, magnet of sequence switch 200, contact 207 (7), front contact and left-hand armature of relay 219, to ground. Sequence switch 200 continues to move until it reaches position 9, by reason of a circuit completed through the master contact 201 to ground. While the sequence switch 200 is moving through position 8 and while it is in position 9, the relay 219 will only remain energized while busy lines are encountered.

In the present arrangement direct lines or lines leading directly to subscribers and private branch exchange lines terminate at the connector switches. To successfully serve these two classes of lines, it is essential to provide special testing means for ascertaining the busy or idle condition of direct lines, and to provide for trunk hunting on the P. B. X. groups of lines. The condition of relay 222 determines whether the connector switch will be restored to normal in case the desired direct line is busy, or whether the connector switch will proceed to hunt for an idle P. B. X. line in the group if the first line in the group be busy. Relays of high resistance, similar to relay 235, are associated with the test conductors of direct lines at the connector and with the test conductor of the last P. B. X. line of the group; 130

while relays of low resistance, similar to relay 228, are associated with the test conductors of other P. B. X. lines. These relays of high and low resistance are in shunt with the relay 222 while the connector is testing busy lines.

If the desired line is a direct line, busy condition will be indicated by raised potential on its test terminal. The source of this 10 raised potential indicated at 232, is applied to the test terminals of busy lines from grounded battery through a resistance like 233 and contact 211 (8 to 15) at a connector similar to the one shown in Fig. 2 by which 15 said busy line has been seized. It will be remembered that relay 219 was energized while sequence switch was in position 7. With relay 219 energized, a test circuit is completed. This circuit may be traced from 20 grounded battery, 232, resistance 233' to point 234 where the circuit divides; one branch extends through the test terminal of the selected line, test brush 238 of the connector, right-hand armature and front 25 contact of relay 219, winding of relay 222 to ground; the other branch extends from point 234 through the relatively high resistance of the winding of relay 235 to ground. The resistance of relay 235 is sufficient to prevent relay 222 from being 30 shunted out. Relay 222 therefore attracts its armatures and completes a circuit to move the sequence switch 200 out of position 9. This circuit may be traced from 35 grounded battery, magnet of sequence switch 200, contact 207 (9), conductor 223, front contact and armature of relay 222, contact 204 (9), conductor 224, left-hand armature and front contact of relay 219, to ground. 40 The sequence switch continues to move until it reaches position 12, by reason of a circuit completed through its master contact 201. As soon as the sequence switch 200 reaches 45 position 10, a locking circuit for relay 219 is established. This circuit may be traced from grounded battery, left-hand winding of relay 219, contact 206 (10 to 14), left-hand front contact and armature of relay 219, to ground. Relay 219 is thereby locked 50 up until sequence switch 200 reaches position 14. In position 12 a circuit is completed for the down-drive or release magnet 225. This circuit may be traced from 55 grounded battery, magnet 225, contact 204 (12), conductor 224, front contact and left-hand armature of relay 219, to ground. As soon as the connector switch is restored to its normal position, a circuit is completed to move the sequence switch 200 from position 12 to position 16. This circuit may be 60 traced from grounded battery, magnet of sequence switch 200, contact 207 (12 to 15), conductor 230, normal contact of commutator 215, commutator brush 231, contact 205 65 (10 to 3), to ground. In position 16, a

busy tone is transmitted to the operator in the well-known manner, through contact 210 (16).

If the desired line is a busy P. B. X. line, this condition will also be indicated by 70 raised potential on its test terminal, but in this case a relatively low resistance is included in the shunt of its test circuit so that the relay 222 will not be energized. The test circuit of the P. B. X. line may be traced 75 from grounded battery, resistance 226, to point 227 where the circuit divides, one branch of which extends through the test contact of the desired line to the test brush 238 of the connector, right-hand armature 80 and front contact of relay 219, relay 222, to ground. The other branch of the circuit extends from point 227, through the low-resistance winding of relay 228, to ground. This relatively low resistance shunts out 85 the relay 222, so that it does not attract its armature. It will be remembered that the sequence switch is now in position 9. In this position the up-drive magnet 218 is energized to move the connector brushes 90 236, 237, 238 through their hunting movement. This circuit may be traced from grounded battery, magnet 218, back-contact and armature of relay 222, contact 204 (9), conductor 224, front contact and left-hand 95 armature of relay 219, to ground. The connector switch continues to hunt until the relay 219 is deenergized. This takes place when the circuit extending from grounded battery, left-hand winding of relay 219, contact 206 (9), conducting segments 220, brush 221, contact 204 (9), conductor 224, left-hand armature and front contact of relay 219, to ground, is interrupted when the original energizing circuit of relay 219 is 100 broken, due to the idle condition of the selected line, and when the brush 221 encounters an insulated segment after the connector brushes are properly centered. When the left-hand armature of relay 219 is retracted, a circuit is completed to move the sequence switch 200 out of position 9. This 105 circuit may be traced from grounded battery, magnet of sequence switch 200, contact 207 (9), back contact and left-hand armature of relay 219, to ground. The sequence switch continues to move until it reaches position 12 by reason of an operating circuit completed at its master contact 201. At this time the left-hand armature of relay 110 219 is still retracted, and an operating circuit to move the sequence switch 200 out of position 12, is completed. This circuit may be traced from grounded battery, magnet of sequence switch 200, contact 207 (12), left-hand armature and back contact of relay 115 219, to ground. The sequence switch continues to move until it reaches position 15 by reason of a circuit completed at its master contact 201. In position 15 the talking 120 125 130

conductors are extended through contacts 209 and 210 (15) to the selected line at the connector and while sequence switch 200 is being moved to this position ringing current is applied to the selected line in the well-known manner.

At the conclusion of the conversation, the supervisory relays 127 are energized in the well-known manner to complete local circuits for lamp signals (not shown). This indicates to the operator that the call has terminated, whereupon she removes plug 114 from the jack 115. The relay 116 deenergizes and retracts its armature, whereupon a circuit is completed to move the sequence switch out of position 16. This circuit may be traced from grounded battery, magnet of sequence switch 100, contact 102 (12 to 16), armature and back contact of relay 116, to ground. The sequence switch 100 continues to move until it reaches position 18, by reason of an operating circuit completed at its master contact 101. In position 18 of this sequence switch, a circuit is completed for the down-drive magnet 128, which may be traced from grounded battery, magnet 128, contact 111 (18), to ground. When the selector switch has reached its normal position, a circuit is completed for moving the sequence switch from position 18 into position 1. This circuit may be traced from grounded battery, magnet of sequence switch 100, conductor 129, contact 106 (18), conductor 130, conducting segment of commutator 125, brush 126 in its normal position, to ground.

When the brushes of the first selector are moved from the test terminal of the selected trunk, the energizing circuit for relay 229 is interrupted. This relay, on deenergizing, completes a circuit for moving the sequence switch 200 from position 15 to position 17, traceable from grounded battery, magnet of sequence switch 200, contact 202 (15 to 16), armature and back contact of relay 229, to ground. Sequence switch 200 continues to move until it reaches position 18, by reason of a circuit completed at its master contact 201. In position 18 of the sequence switch 200 a circuit is completed for the down-drive magnet 225. This circuit may be traced from grounded battery, magnet 225, contact 205 (18), to ground. When the connector reaches its normal position, a circuit is completed to move the sequence switch 200 out of position 18 into its normal position. This circuit may be traced from grounded battery, magnet of sequence switch 200, contact 202 (18), conductor 230, conducting segment of commutator 215, brush 231, contact 205 (10 to 8), to ground.

It has been found in practice that the test circuits will operate most satisfactorily when the relays and resistance coils included therein are adjusted to the following resistances: relay 222 of five hundred ohms; the

windings of the relay 219 each having a resistance of five hundred ohms; resistance of coil 233 being three hundred ohms; resistance of coil 233' being three hundred ohms; resistance of relay 235 being four hundred ohms; the resistance of relay 228 being one hundred ohms. It will be understood that these resistance values may be varied as best suits the needs of the service without departing from the spirit of this invention.

What is claimed is:

1. In a telephone system, an incoming line, outgoing lines, a switch, means controlled at a distant point for causing said switch to select a particular outgoing line, releasing means for said switch, a test conductor associated with each of the outgoing lines and terminating in said switch, means for supplying to the terminals of all of said test conductors current of the same polarity, and a double wound relay controlled by means of one of its windings over said test conductors for causing the further operation of said first mentioned means and said releasing means.

2. In a telephone system, an incoming line, outgoing lines, a switch, means controlled at a distant point for causing said switch to select a particular outgoing line, releasing means for said switch, a test conductor associated with each of the outgoing lines and terminating in said switch, means for supplying to the terminals of all of said test conductors current of the same polarity, a relay controlled in part over test conductors of outgoing lines, and means controlled in part by said relay for causing the further operation and release of said switch.

3. In a telephone system, an incoming line, outgoing lines, means for rendering said outgoing lines busy, a test conductor associated with each of the outgoing lines, a switch, means controlled at a distant point for operating said switch to seize a particular outgoing line, terminals for said switch in which said outgoing lines and said test conductors terminate, means for supplying the terminals of the test conductors associated with busy lines with current of the same polarity, releasing means for said switch, a relay controlled in part over the test conductors of the busy lines, and a marginal relay controlled by said first mentioned relay for causing the further operation and release of said switch.

4. In a telephone exchange system, a switch having an active contact and a plurality of passive contacts, means for supplying the latter with current of the same polarity, a variable operable sending device, means for causing said switch to seize any passive contact in accordance with the adjustment of such sending device, a release magnet for said switch, and a single means

for controlling the actuation of said release magnet and the further operation of said switch.

5. In a telephone exchange system, a selectively operable switch, said switch being provided with passive and active contacts, said passive contacts being connected to the same pole of battery and arranged for engagement by said active contacts, a release magnet for said switch, a relay for controlling the actuation of said release magnet in response to the engagement of a test contact, means controlled by said relay for preventing the actuation of said release magnet upon the engagement of a certain other test contact, an energizing circuit for said relay, and a holding circuit for said relay including an active contact of said switch.
- 20 6. In a telephone exchange system, a connector switch, releasing means for said connector switch, a plurality of lines belonging to two classes, a test conductor supplied with current of the same polarity associated with each of said plurality of lines, means for rendering any one of said lines busy, means for causing said connector switch to engage any one of said lines, means operative if the engaged line belongs to one class and is busy for immediately operating said releasing means, means operative if the engaged line belongs to the other class and tests busy for delaying the actuation of said releasing means until the connector has engaged all the lines belonging to said other class and such lines are busy, and a single means for controlling said two last mentioned means.

7. In a telephone system, a plurality of lines, a plurality of selectively operable switches, a test conductor associated with each one of said lines, all of said test conductors being normally connected to the same pole of battery, means at each one of said switches for causing it to engage any one of said lines and its associated test conductor, means operative thereupon for connecting the engaged test conductor to the opposite pole of battery, releasing means for each of said switches, means for releasing a switch which is caused to engage the test conductor associated with a certain line and connected to said opposite pole of battery, means for causing said last mentioned switch to engage the test conductor of another line if said switch was caused to engage a certain test conductor connected to the opposite pole of battery, and a single means for controlling said last two means.

- 60 8. In a telephone system, a plurality of lines, a plurality of selectively operable switches, a test conductor associated with each one of said lines, all of said test conductors being normally connected to the same pole of battery, means at each one of

said switches for causing it to engage any one of said lines and its associated test conductor, means operative thereupon for connecting the engaged test conductor to the opposite pole of battery, releasing means for each of said switches, means for releasing a switch which is caused to engage a test conductor connected to the opposite pole of battery, means for causing said last mentioned switch to engage the test conductor of another line if said switch is caused to engage a certain test conductor connected to the opposite pole of battery, and a margin relay for directly controlling said last two means.

9. In a telephone system, two groups of test conductors each having two branches, means including a relatively high resistance for supplying the test conductors of one group through one of their branches with current of a certain polarity, means including a relatively low resistance for supplying the test conductors of the other group through one of their branches with current of said certain polarity, means for supplying all said test conductors through their other branches with current of the opposite polarity, a connector switch, means for operating it to engage any one of said test conductors, releasing means for said switch, a marginal relay arranged to be connected to said test conductors during the operation of said connector switch, means operated directly by said relay when in circuit with a high resistance for causing the release of said switch, and means controlled directly by said relay when in circuit with a low resistance for causing the further operation of said switch.

10. In a telephone exchange system, a connector switch, a movable contact and a plurality of stationary contacts for said switch, a plurality of conductors each leading from one pole of battery to each of said stationary contacts, a relay, means for connecting said relay to the movable contact of said switch, means for rendering all said stationary contacts busy, means for operating said switch to move its movable contact onto one of said said stationary contacts, releasing means for said movable contact actuated under the control of said relay if said last mentioned stationary contact tests busy, means for moving said movable contact into engagement with another one of said stationary contacts, automatic means operative under the direct control of said relay if said last mentioned stationary contact is busy for causing said movable contact to move over a group of said stationary contacts, and means also controlled directly by said relay for causing the operation of said releasing means to terminate the last mentioned operation of said movable contact only if the last stationary contact of said group is busy.

11. In a telephone system, a switch having active contacts including a single test contact and a plurality of passive contacts, outgoing lines and associated test conductors terminating in said passive contacts, means for supplying current of the same polarity to the contacts of all of said test conductors, means controlled from a distant point for causing said switch to seize a particular outgoing line, releasing mechanism for said switch, means controlled over said test conductors for effecting the automatic hunting operation and release of said switch, and an operating and holding circuit for said last mentioned means.
12. In a telephone system, a switch having active contacts including a single test contact and a plurality of passive contacts, outgoing lines and associated test conductors terminating in said passive contacts, means for supplying current of the same polarity to the contacts of all of said test conductors, means controlled from a distant point for causing said switch to seize a particular outgoing line, releasing mechanism for said
13. In a telephone system, a switch having active contacts including a single test contact and a plurality of passive contacts, outgoing lines and associated test conductors terminating in said passive contacts, means for supplying current of the same polarity to the contacts of all of said test conductors, means controlled from a distant point for causing said switch to seize a particular outgoing line, releasing mechanism for said switch and a marginal relay controlled over said test conductors for directly affecting the automatic operation and release of said switch.

In witness whereof, I hereunto subscribe my name this 19th day of October A. D., 1916.

ALBEN E. LUNDELL.
